UNITED STATES PATENT OFFICE.

WILLIAM HENRY HARRINGTON, OF HARTFORD, CONNECTICUT, ASSIGNOR TO THE ARROW ELECTRIC COMPANY, OF HARTFORD, CONNECTICUT, A CORPORATION OF CONNECTICUT.

DESIGN FOR AN ATTACHMENT-PLUG BASE.

Application filed June 26, 1923. Serial No. 6,588. Term of patent 14 years.

To all whom it may concern:

Be it known that I, WILLIAM HENRY HARRINGTON, a citizen of the United States of America, residing at Hartford, in the county of Hartford and State of Connecticut, have invented a new, original, and ornamental Design for an Attachment-Plug Base, of which the following is a specifica-

tion, reference being had to the accompanying drawing, forming part thereof.

The figure is a plan view of an attachment plug base embodying my new design.

I claim:

The ornamental design for an attachment plug base, as shown.

WILLIAM HENRY HARRINGTON.
